UNITED STATES PATENT OFFICE.

SCOTTY HANCOCK, OF SHIDLER, OKLAHOMA.

COMBINATION BIT AND UNDERREAMER.

Application filed April 25, 1924. Serial No. 708,987.

To all whom it may concern:

Be it known that I, SCOTTY HANCOCK, a citizen of the United States, residing at Shidler, in the county of Osage and State of Oklahoma, have invented certain new and useful Improvements in a Combination Bit and Underreamer, of which the following is a specification.

This invention relates to a combination bit and underreamer, and it consists in the novel features hereinafter described and claimed.

An object of the invention is to provide a tool including a drill bit and an under reamer, and adapted to be used in drilling wells, and which will drill and underream or clean out the well, both operations taking place simultaneously.

A further object of the invention is to provide means for resiliently and slidably holding the reamer bit upon the shank of the drill bit, so that they may operate in the earth below the lower edge of the well casing, and cut the earth to allow space for the lowering of the casing in the hole.

With these objects in view, the structure includes a drill bit provided at its side with longitudinally disposed recesses, the said recesses having in their opposite side walls grooves adapted to receive flanges, which are provided upon the reamer bit, and whereby the said reamer bits may move longitudinally of the shank of the drill bit. Longitudinally extensible members are pivotally connected at the sides of the shank member of the drill bit and are connected with the reamer bit. The said longitudinally extensible elements consist of overlapping sections and springs are provided for normally holding the reamer bit toward the upper end of the shank of the drill bit. When the drill bit is moved in an upward direction, the reamer bit may encounter the earth below the lower edge of the well casing, or they may encounter the lower edge of the casing, and thus they are held at fixed points while the drill bit continues in its upward movement. At such time, the springs are contracted longitudinally and the sections of the connecting means may move longitudinally with relation to each other. When the drill bit descends, the said springs expand longitudinally and the sections of the connecting means move with relation to each other correspondingly until such time as

groove where all of the parts descend together.

In the accompanying drawing:

Figure 1 is a side elevation of the combination drill bit and underreamer, with parts broken away, and parts shown in section.

Figure 2 is a side elevation of the combined bit and under reamer, viewing the same at the side thereof, which is disposed at a right angle to the side shown in elevation, in Figure 1.

Figure 3 is a perspective view of one of the reamer bits detached.

The combination bit and under reamer includes a drill bit 1, having a shank 2, and which may be connected with a drill rod (not shown), in a usual manner. The shank 2 is provided at its side with one or more longitudinally disposed recesses 3, having at the opposite side walls longitudinally disposed grooves 4. At the upper ends, the recesses 3 are enlarged, as at 5, and shoulders 6 are provided at the lower ends of the said enlargements. At the upper ends, the recesses 3 are provided with sockets 7, which are formed in the upper portion of the shank 2, and as best indicated in Figure 2 of the drawings.

The device also includes one or more reamer bits 8, which are provided, at their opposite sides, with flanges 9, adapted to be slidably received in the grooves 4. Recesses 10 are formed in the upper ends of the bits 8, and are disposed transversely of the bit, said recesses being provided at their lower portions, with diametric enlargements 11. The recesses 10 and the enlargements 11 thereof are disposed at acute angles to the inner faces of the bits 8, as best indicated in Figure 1 of the drawings. The device also includes bars 12, provided at their upper ends with head portions 13, which are pivotally received in the sockets 7. The lower portions of the bars 12 are slotted longitudinally as at 14. The bars 12 are normally received in the upper portions of the recesses 3. Bars 15 are provided at their upper portions with longitudinally disposed recesses 16, and the bars 12 and 15 are linked together at their recessed portions, as the end parts of the respective bars, pass through the slots of the co-acting bar. Pins 17 are carried at the upper portions of the bars 15, and coil springs bear at their upper ends against the springs 17, and at their lower ends 110

against the shoulders 6, provided at the opposite side walls of the recesses 3. The bars 15 are provided at their lower ends with heads 19, which are slidably received in the 5 enlargements 11, of the grooves 10, of the reamer bits 8.

The recesses 3 are deeper at their lower ends, as at 20, than at their upper portions, in order that the reamer bit 8 may be moved 10 down, into the lower portion of the said recesses, and into the deeper part 20 thereof. When this is done, the bit 8 may be moved transversely of the shank 2, whereby the head 19 of the bar 15, may be moved out 15 of the outer end of the recesses 10 of the said bit. By reversing this operation, the bars may be connected with the bit.

As the drill bit 1 is reciprocated, during the operation of drilling the well in the earth, 20 the bit 8 will work in the earth, under the lower edge of the well casing, and cut the earth so that the casing may be readily lowered in the well. During the upward movement of the shank 2, should the upper portions 25 of the bit 8 strike the lower edge of the well casing, the bit 8 will come to a state of rest, while the shank 2 continues its upward movement. Thus, the springs 18 are compressed longitudinally, and the bars 15 move 30 longitudinally with relation to the bars 12. When the shank 2 descends, the spring 18 expands, whereby the bars 15 move upwardly along the descending bars 12, until the flanges 9 of the bit 8 encounter the upper ends of 35 the grooves 4, when all of the parts descend in the well together.

Having described my invention, what is claimed is:

1. A combined drill bit and underreamer 40 comprising a shank provided at its side with a longitudinally disposed recess having grooves in its opposite side walls, a reamer bit having at its opposite sides flanges, which are slidably received in said grooves, a longitudinally extensible element consisting of 45 overlapping bar sections connected at one end

with the shank and at its other end with the reamer bit, and spring means engageable with the shank and adapted to normally hold the flanges of the reamer bit against the 50 end walls of the grooves in the shanks.

2. A combined drill bit and underreamer comprising a shank having at its side a longitudinally disposed recess provided at its opposite side walls with longitudinally disposed grooves, a reamer bit having outstanding flanges, which are slidably received in said grooves, said reamer bit being provided at its upper ends with a transversely disposed recess, which is diametrically enlarged 55 at the inner portion of the bit, overlapping bar sections, one of the said bar sections having a head which is pivotally mounted upon the shank, and the other section having a head which is slidably received in the recess 60 of the reamer bit, said bar sections being interlinked with each other, and a spring bearing against the shank, and one of the bar sections, and serving to hold the flanges of the reamer bit against the end of the groove 70 in the shank.

3. A combined drill bit and underreamer comprising a shank provided at its side with a longitudinally disposed recess having grooves at its opposite side walls, a reamer 75 bit provided at its opposite sides with flanges, which are slidably received in said grooves, the said reamer bit being provided at its upper end with a transversely disposed recess, overlapping bar sections interlinked with 80 each other, one of the said bar sections being provided at its upper end with a head, which is pivotally connected with the shank, and the other bar section being provided at its lower end with a head, which is detachably 85 received in the recess of the reamer bit, and a spring bearing against the last mentioned bar section and located in the recess in the shank, and having its lower end bearing 90 against the shoulder provided in said recess.

In testimony whereof I affix my signature.
SCOTTY HANCOCK.
